UNITED STATES PATENT OFFICE.

ROSWELL A. MOORE, OF WATERBURY, CONNECTICUT, ASSIGNOR TO WATERBURY BUCKLE COMPANY, OF WATERBURY, CONNECTICUT, A CORPORATION OF CONNECTICUT.

PIN-TICKET.

1,174,087.

Specification of Letters Patent. Patented Mar. 7, 1916.

Application filed September 22, 1915. Serial No. 51,980.

To all whom it may concern:

Be it known that I, ROSWELL A. MOORE, a citizen of the United States, residing at Waterbury, in the county of New Haven 5 and State of Connecticut, have invented certain new and useful Improvements in Pin-Tickets, of which the following is a specification.

My invention relates to pin or marking 10 tickets to be attached to cloth or other articles and my objects are the production of tickets which will not catch one in another in the mass and which will be stiffened or reinforced in such manner that the liability of accidental bending or pulling up 15 on articles to which they are attached will be reduced to a minimum and without increasing the cost of production.

In the drawing Figure 1 is a view of a 20 pin ticket embodying my improvements; Fig. 2 an edgewise view at the pin end and Fig. 3 a sectional view showing the pin attachment.

The complete ticket consists of the usual 25 tab 1 of cardboard or other suitable material of any desired size or shape and the pins or prongs 2 secured adjacent to one edge for the purpose of attaching the ticket to the goods.

30 The pin fasteners 2 are formed up as a U-shaped piece with the pointed prongs 3-3 stuck through the tab 1 at a short distance from one edge. The U is bent over parallel to the surface of the tab at 4 and 35 around the edge at 5 and back on itself at 6, so that the parts 4 and 6 are approximately parallel with the tab 1 firmly clamped between them.

The foregoing description is not neces-

sarily a recital of the precise steps followed 40 in the process of manufacture but is descriptive of the resultant structure.

The part 6 is forced inwardly so that it embeds itself in the tab as shown in Figs. 2 and 3. This inward bending results in imparting two important functions to the ticket. First:—The part 6 being driven 45 into and lying below the plane of the body of the ticket prevents the corners and edges of other tickets being caught between the 50 wire and the tab when the tickets are in a mass. Second:—Setting the metal into the tab at 6 gives a slight transverse curvature to the tab adjacent to that edge as shown in Fig. 2 and this stiffens the ticket longitudinally so that when on the goods the 55 ticket is not liable to be caught and lifted in handling, causing it to break at the pin, as commonly occurs with tickets of the ordinary type.

60 The ticket is used in the ordinary way, the prongs 3-3 being pushed through the goods and bent over.

I claim:—

65 A pin ticket consisting of a tab, fastening prongs secured thereto, said prongs being formed of a single piece of wire bent to form a U with the bottom of the U bent around an edge of the tab and forced below the plane of the body of the tab whereby said 70 tab has a transverse curvature stiffening the same longitudinally.

75 In testimony whereof I have affixed my signature in presence of two witnesses.

ROSWELL A. MOORE.

Witnesses:

EMILY FRANEK,
ALTA L. CODDINGTON.
